UNITED STATES PATENT OFFICE.

RICHARD B. CHARLTON, OF MILWAUKEE, WISCONSIN, ASSIGNOR TO THE
CONTINUOUS RAIL JOINT COMPANY OF AMERICA, A CORPORATION OF
NEW JERSEY.

APPARATUS FOR COOLING FISH-PLATES IN THE PROCESS OF MANUFACTURE.

SPECIFICATION forming part of Letters Patent No. 691,355, dated January 21, 1902.

Application filed December 15, 1900. Serial No. 39,964. (No model.)

To all whom it may concern:

Be it known that I, RICHARD B. CHARLTON, a citizen of the United States, residing at Milwaukee, in the county of Milwaukee and State 5 of Wisconsin, have invented certain new and useful Improvements in Apparatus for Cooling Fish-Plates in the Process of Manufacture; and I do hereby declare the following to be a full, clear, and exact description of the 10 invention, such as will enable others skilled in the art to which it appertains to make and use the same, reference being had to the accompanying drawings, and to letters of reference marked thereon, which form a part of 15 this specification.

This invention relates to the manufacture of railway fish-plates or rail-joints, and particularly that fish-plate or joint shown in United States Patent No. 637,723, granted to

20 Frederick T. Fearey, November 21, 1899.

More especially the invention relates to the cooling of the fish-plates in the process of manufacture, the objects being to provide a device for automatically handling the fish-25 plates throughout said cooling operation, to regulate the position of the fish-plates as they enter the cooling-tank, to secure a plunging of the fish-plate into the tank in a sidewise position, whereby different points along its 30 length are simultaneously cooled, to thus prevent warping and twisting of the fish-plate in cooling, and to secure other advantages and results, some of which may be referred to hereinafter in connection with the description 35 of the working parts.

The invention consists in the improved apparatus for cooling fish-plates in the process of manufacture and in the arrangements and combinations of parts of the same, all substantially as will be hereinafter set forth, and 40 finally embraced in the clauses of the claim.

Referring to the accompanying drawings, in which like letters of reference indicate corresponding parts in each of the several views, 45 Figure 1 is a plan of the apparatus. Fig. 2 is a side elevation of the receiving-conveyer and its guides. Fig. 3 is a side elevation, partly in section, on line x, Fig. 1, of the feeding device and cooling-tank. Fig. 4 is a 50 vertical section of the feeding device, taken

on line y, Fig. 3. Fig. 5 is another cross-section taken through the cooling trough or tank on line y', Fig. 3, and looking toward the feeding device. Fig. 6 is a plan of a portion of the cooling-tank conveyer and its track. Fig. 55 7 is a sectional view on line z, Fig. 6; and Fig. 8 is a section on line z', Fig. 7.

In said drawings, *a* indicates a conveyer, which preferably consists of an endless belt made up of transverse slats or strips *a'*, hinged together at their adjacent edges, the whole being provided at its sides with wheels or casters *a''*, running on a track *a'''* and having between the rows of casters a chain belt *a''''*, adapted to be engaged by sprocket-wheels *a''''* 65 to transmit motion to the conveyer. Any other construction of conveyer adapted to transport the fish-plates may be used, however.

The fish-plates are usually delivered upon 70 this conveyer *a* from the sawing-machine, which has cut them into proper lengths, and several of them fall upon the conveyer at once, lying end to end in a transverse row across the conveyer. They are then carried by 75 the conveyer against fixed pins *b*, one of which engages each plate at a point between its center and one of its ends, and thus the plates are turned at right angles to their former position, or nearly so, and pass in between guideways *c*, which compel the plates to travel along the conveyer in endwise position thereon and side by side with relation to each other. Said guideways *c* are supported

slightly above the conveyer in any suitable 80 manner, and the turning-pins *b* preferably depend from a transverse bar *b'*, held in horizontal position above the conveyer by legs or stands *b''*, having slots or slideways *b'''*, in which the pins are adjustable. After being 85 brought into proper lengthwise position on the conveyer *a* by the guides *c* the fish-plates are passed from said conveyer onto another conveyer *d*, forming a part of the feeding device. This feeding-conveyer *d* moves at 90 right angles to the direction of movement of the conveyer *a*, the end of the conveyer *a* being closely adjacent to one side of the feeding-conveyer *d*, as shown in Figs. 1 and 5, and the fish-plates are deposited on the said 100

feeding-conveyer transversely of its length and at short distances apart. To bring the series of fish-plates thus deposited upon the feeding-conveyer *d* into alignment so that 5 their ends are even, I employ a stop-bar *e* at the opposite side of the feeding-conveyer *d* from where the fish-plates are delivered by the conveyer *a* and against which the fish-plates may strike and be stopped as they are 10 slid onto the feeding-conveyer *d*. Said stop-bar is supported by plunger-like arms or extensions *e'*, projecting rearward through blocks *e²* and having springs *e³* between said blocks and the stop-bar to secure a relative 15 freedom between the bar and fish-plates, so that the fish-plates will travel with the conveyer *d* without materially dragging against the stop-bar. The blocks *e²* in turn slide in ways *e⁴* and are adjusted by screws *e⁵* to secure the proper position of the stop-bar for 20 different lengths of fish-plates.

The feeding-conveyer *d* carries the fish-plates forward to the cooling-tank conveyer *f*; but instead of being transferred directly 25 to the said cooling-tank conveyer the plates are transferred by a tilting table *g*, which insures their being placed on the cooling-tank conveyer at exactly right angles to the direction of movement, any irregularity of disposition 30 on the feeding device being thereby corrected. This tilting table is disposed at the end of the feeding-conveyer *d*, being preferably pivoted on the shaft *i'* of the sprocket-wheel driving said conveyer, so that the fish-plates pass easily onto the table, a counter-weight *g'* serving to keep the table elevated 35 unless overbalanced by the weight of a fish-plate.

To insure that the table shall not tip to discharge a fish-plate until both ends of the plate 40 rest upon the table, thus securing proper right-angular position of the fish-plate, the table has at each side a trip-plate *h*, hinged at its forward end on the table and at its rear 45 end having a pawl *h'*, extending downward into engagement, under normal conditions, with a stop *h²* on the standards *i* or other fixed part of the machine. A spring *j*, pressing upward on such trip-plate, normally holds its 50 pawl *h'* in engagement with the stop *h²*; but under the weight of a fish-plate the trip-plate *h* is depressed against the spring *j* and its pawl released. The table will not tilt, however, until both pawls are released, and hence 55 the fish-plate must lie straight across the table, so as to engage both trip-plates before it can be discharged.

When the tilting table tips, the fish-plate passes therefrom by an incline *k* to the guide-rails *l* of the cooling-tank, across which rails it lies transversely, ready to be caught and carried along by dogs *q* on a chain conveyer *m*, running through the tank or trough. Said cooling-tank *n* is preferably about thirty-two 60 inches (more or less) wide and seventy feet (more or less) long and is supported by legs or supports *n'* in any suitable way. Sprocket-

wheels *o* are arranged at the ends of the trough, and over these runs the chain conveyer *m*, before referred to, said conveyer following the track *l* into the tank at its upper side and returning beneath the tank, as shown in Fig. 3.

The guide-rails *l* extend from sprocket-wheel to sprocket-wheel above the tank and 70 at the ends of said tank incline gradually down into the tank and extend along the bottom submerged. These rails are in practice about fourteen inches (more or less) apart and have recesses or grooves *l²* in their facing sides, adapted to provide runways for the opposite wheels *p'* of small trucks *p*, placed about eight inches apart and connected along their centers by the chain *m*. The tops of the rails form slideways along which the fish-85 plates may be pushed in transverse position, such pushing being accomplished by dogs *q*, projecting up from the trucks *p* to engage the fish-plates from behind as they lie across the rails. 90

It will be noted that by means of my tipping table *h* and the dogs *q* on the cooling-tank conveyer the fish-plates approach the water of the cooling-tank parallel to the surface thereof, and when they are submerged 95 all points along the length of the fish-plates strike the water at the same instant, so that there is no cooling of one end portion of the fish-plate while the other end is still hot, which results in warping or twisting the fish-plates. By my improved appliances the fish-plate is cooled uniformly along its length and a more true and perfect fish-plate secured. 100

The cooling-tank has a supply of running cold water, which is kept at a depth of about 105 twenty-four inches, and when the fish-plates are delivered at the opposite end of the trough from where they entered they are sufficiently cooled for punching or such other operations as they are to be next subjected to. As they 110 then come out of the water on the conveyer *f* they can be received into any suitable receptacle or upon another traveling conveyer, as may be desired. The conveyer *f* returns beneath the tank *n* on a supporting-track *r*. 115

Having thus described the invention, what I claim as new is—

1. In an apparatus for cooling fish-plates or the like, the combination with a cooling-tank, of rails *l*, extending through the tank 120 and forming a slideway on which the fish-plates may lie transversely, and a belt adapted to travel longitudinally of said slideway and having dogs to engage fish-plates lying on the slideway. 125

2. In an apparatus for cooling fish-plates or the like, the combination with a cooling-tank, of rails *l*, extending through said tank and providing at their upper surface a slideway for fish-plates to lie across, a belt adapted 130 to travel longitudinally of said rails, cross-pieces on said belt engaging a lower surface of the rails and held below the level of the slideway and dogs on said cross-pieces pro-

- jecting upward to engage fish-plates on the slideway.
3. In an apparatus for cooling fish-plates, the combination with a cooling-tank, of rails 5 *l*, extending through the tank and providing at their upper surfaces a slideway for transversely-disposed fish-plates and having their facing sides longitudinally grooved, a belt adapted to travel longitudinally of said rails, 10 cross-pieces attached to said belt with wheels at the ends working in said grooves, and dogs on said cross-pieces extending above the slideway.
4. In an apparatus for cooling fish-plates, 15 the combination with a bath or tank, of a slideway extending through said tank and being adapted to directly support a fish-plate at points at or near its opposite ends and hold the same always horizontal, and means for 20 sliding the fish-plates along said slideway.
5. In an apparatus for cooling fish-plates, the combination with a bath or tank, of two rails extending through the said bath or tank and adapted to support a fish-plate from below at two points near its ends, whereby the 25 exterior surface of the fish-plate is freely exposed to the bath, and means for sliding fish-plates along said rails in position substantially at right angles thereto.
- 30 6. The combination of the tank *n*, having sprocket-wheels *o*, arranged at each end, an endless conveyer running over said sprocket-wheels and through the tank and returning beneath the tank and being adapted to carry 35 fish-plates or the like through the tank, an incline *k*, above the conveyer, and means for feeding fish-plates down said incline in transverse positions with respect to the conveyer, substantially as set forth.
- 40 7. The combination with a conveyer *a*, adapted to receive fish-plates lying end to end in a transverse line across the conveyer, of turning-pins *b*, arranged vertically above the conveyer, and guides *c*, beyond said pins, 45 whereby the fish-plates are each turned at right angles to its former position, substantially as set forth.
8. The combination with a conveyer *a*, adapted to receive a fish-plate or the like lying 50 transversely across the conveyer, of a vertical pin *b*, above the conveyer independent thereof, and adapted to engage the fish-plate intermediate of its center and one of its ends as the same is carried forward by the 55 conveyer, substantially as set forth.
9. The combination with a conveyer *a*, adapted to transport a transverse series of parallel fish-plates or the like lying longitudinally of the conveyer, of a second conveyer 60 *d*, moving at right angles to the direction of movement of the first-mentioned conveyer and having its side closely contiguous to the end of said first-mentioned conveyer, whereby the fish-plates are deposited by the first conveyer directly upon the second conveyer as a 65 longitudinal series of fish-plates each disposed transversely of the said second conveyer.
10. The combination with a broad conveyer *a*, adapted to transport transverse series of longitudinally-disposed fish-plates or the like, of a narrow conveyer *d*, moving at right angles to the direction of movement of the broad conveyer, and having one of its sides closely contiguous to an end of the broad conveyer, the fish-plates being deposited by the first-mentioned conveyer directly upon the second in transverse position, and an elastically-supported adjustable stop-bar at the opposite side of the narrow conveyer from the delivery end of the broad conveyer, substantially as set forth. 70
11. The combination with a conveyer *d*, adapted to carry fish-plates or the like, lying transversely of its direction of movement, of a tilting table hinged at the end of said conveyer and onto which each fish-plate falls, 80 said tilting table having at each side tripping means which must be engaged by the opposite ends of the fish-plate to cause a tipping of the table, substantially as set forth. 85
12. The combination with a conveyer, of a tilting table adapted to receive fish-plates or the like from said conveyer and drop them in a position at right angles to the direction of movement of the conveyer, said tilting table 90 being pivoted on horizontal bearings and adapted to fall under the weight of a fish-plate, and said table having at its opposite sides independent retaining means which must be simultaneously engaged by the opposite ends of a fish-plate to release the table, 95 substantially as set forth. 100
13. The combination with a conveyer, of a tilting table adapted to turn on a horizontal axis under the weight of a fish-plate or the like and having a counterbalance normally holding it in position, said table having a plurality of independent pawls engaging fixed stops to lock the table in normal position, and trip-plates each connected to a pawl and 105 adapted to release the same when depressed by a fish-plate, substantially as set forth. 110
14. The herein-described tilting table for dropping fish-plates or the like in a predetermined position, having a pivoted body portion adapted to tip under the weight of a fish-plate, and said body portion having separate and independent catches locking it in elevated position and adapted to be released only by simultaneous engagement by different parts of the fish-plates, substantially as 115 set forth. 120
15. A tilting table for dropping fish-plates or the like in a given position, having a pivoted body portion, and independent pawls on 125 said body portion engaging fixed stops to lock the table against tipping, said pawls being adapted to be simultaneously engaged by opposite end portions of the fish-plate before the table will be free to tip under the weight 130 of the fish-plate, substantially as set forth.
16. In a tilting table, the combination of a body portion, tripping-plates hinged on said body portion and having pawls adapted to

normally engage fixed stops and lock the table in elevated position, springs holding said tripping-plates with their pawls in locking position, and a counterbalance adapted to re-store the table to elevated position after discharging its contents, substantially as set forth.

In testimony that I claim the foregoing I have hereunto set my hand this 12th day of December, 1900.

RICHARD B. CHARLTON.
